UNITED STATES PATENT OFFICE.

RALPH H. GREEGOR, OF COLUMBUS, OHIO, ASSIGNOR TO THE KINNEAR MANUFACTURING COMPANY, OF COLUMBUS, OHIO, A CORPORATION OF OHIO.

MOVABLE DOORPOST AND LATCHING MEANS THEREFOR.

Application filed November 20, 1922. Serial No. 602,012.

To all whom it may concern:

Be it known that I, RALPH H. GREEGOR, a citizen of the United States, residing at Columbus, in the county of Franklin and 5 State of Ohio, have invented a certain new and useful Improvement in Movable Doorposts and Latching Means Therefor, of which the following is a specification.

This invention relates to door posts and 10 their operating and latching means of the kind shown, for example, in the United States patent to Edward H. McCloud, No. 1,283,836, dated November 5, 1918, and the invention has for its object to simplify the 15 construction and dispense with an elaborate mechanism to release the post latch and thereby render such a construction less expensive and make it equally, if not more, certain and efficient in operation.

20 The invention is embodied in the example herein shown and described.

In the accompanying drawings—

Figure 1 is a side view showing the door post in closed and latched position.

25 Fig. 2 is a similar view showing the post raised.

Fig. 3 is a side view on a larger scale broken out showing the post in closed and latched position.

30 Fig. 4 is a side view of the lower end of the post unlatched and partially removed from latched position.

Fig. 5 is a front view of the post partially broken out.

35 Fig. 6 is a cross section of the post.

Fig. 7 is a detail in vertical section of the weight and the latch it carries pivoted thereto.

The post includes, in the instance shown, 40 an angle member 17 secured to channels or guides 17^a hinged at 18 to end brackets 19. The end brackets 19 support the shafts of rolling metallic doors (not shown) the edges of which travel in the channels 17^a. The 45 character 29 designates a weight that travels on guiding edges 17^b on the angle member 17. The weight carries in its lower end a latch 20 pivoted at 20^a to the weight said latch being provided with a toe 20^b striking 50 against a shoulder in the weight so as to permit it to swing on a small arc across a radius substantially at right angles to the post 17. The weight 29 has secured to it a light cable 32 that is passed upward around 55 a pulley 27^a journaled between brackets 27

on the upper end of the member 17. The free end of the cable 32 has attached to it a small pulley 34. The lower end of the post has attached to it a rigid extension 35 to which is attached a stout cable 33, which cable is extended upward around the pulley 34 to a point where power may be applied to it for drawing it to raise the post and from which it may be released for lowering the post to closing position.

60 65 21 is a stop on the floor for arresting the post at its closed position and 22 is a stop on the floor behind which the latch falls when the post is in closed position to prevent the post from swinging inward until 70 operated by the cable.

The operation is as follows: When the post is in closed position the stout cable 33 is flexed as shown in Fig. 1, and when the cable is drawn upon with sufficient force it 75 tends to straighten as shown by broken lines in that view. Such draft on the cable 33 draws down on the free end of cable 32 and up on the weight thereby lifting the weight and with it the latch 20 from engagement 80 with the stop 22 as illustrated in Fig. 4. After this release of the latch further draft on the cable 33 may be used to raise the post as far as the position indicated in Fig. 2 if desired. To lower the post to closing position the cable 33 is released and slackened thereby lowering post and the weight until the latch 20 drops behind the stop 22.

85 The fact that most of the weight is at one side of the hinge 18 as shown causes the 90 post to swing readily toward the stop 21.

The forms of the parts can be changed without departing from the gist of the invention as claimed.

95 What I claim is:

1. In combination with a swinging post provided with a pulley at its upper portion, a sliding weight on the post, a latch carried by said weight, a cable attached to said weight and passed over said pulley, a second cable connected with the lower end of the post and slippingly engaging the free end of said first named cable and a stop engaged by said latch when the post is in closed position.

100 105 2. In combination with a swinging post provided with a pulley at its upper portion, a sliding weight on the post, a latch carried by said weight and pivoted to the weight to swing on a short arc intersecting a line 110

substantially at right angles to the post, means for raising said post and for raising said weight and a stop engaged by said latch when the post is in closed position.

- 5 3. In combination with a swinging post provided with a pulley at its upper portion, a sliding weight on the post, a latch carried by said weight and pivoted to the weight to swing on a short arc intersecting a line

substantially at right angles to the post, a 10 cable attached to said weight and passed over said pulley, a second cable connected with the lower end of the post and slippingly engaging the free end of said first named cable, and a stop engaged by said 15 latch when the post is in closed position.

RALPH H. GREGOR.
